by his Atty *John D. Sprague*

UNITED STATES PATENT OFFICE.

DAVID KENNEDY, OF DETROIT, MICHIGAN, ASSIGNOR TO KENNEDY & GREIG, OF SAME PLACE.

ELEVATOR.

SPECIFICATION forming part of Letters Patent No. 315,634, dated April 14, 1885.

Application filed August 2, 1884. (No model.)

To all whom it may concern:

Be it known that I, DAVID KENNEDY, of Detroit, in the county of Wayne and State of Michigan, have invented new and useful Improvements in Elevators; and I do hereby declare that the following is a full, clear, and exact description thereof, reference being had to the accompanying drawing, which form a part of this specification.

10 This invention relates to certain new and useful improvements in elevating mechanism such as is employed for raising and lowering platforms or carriages in elevator-shafts or for similar purposes, by means of which improvements a perfect control of the speed is obtained and a certain means had for arresting the platform or elevator at any desired point.

15 In the accompanying drawing, which forms a part of this specification, A represents a steam-cylinder designed to be placed at any convenient point near the elevator-shaft, and is open at its top, the only head of the cylinder being the one at the bottom thereof.

20 B is a piston-rod, to which the piston C is rigidly attached. Immediately above this steam-piston and resting upon a frame, D, upon the top of such steam-cylinder, and in axial line therewith, is the cylinder E, provided with the piston F, passing through proper 25 stuffing-boxes, G, in the bottom of the cylinder E and projecting through similar stuffing-boxes, H, in the top of said cylinder E. A communication between the upper and lower ends of the cylinder E is had by means of the passage 30 I, terminating at each end in contracted ports a, the one leading into the top of the cylinder E and the other into the bottom thereof. In the passage I, which is formed by a suitable pipe, are plug-valves J and a cut-off valve, K.

35 L is a tank having a mouth, b, through which it may be filled, and the tank communicates by means of a pipe, M, having a cut-off valve, N, therein, with the passage I. The upper end of the piston B is secured to a suitable 40 frame, O, carrying a series of sheaves or pulleys, P.

45 In practice, steam is admitted from the steam-chest Q through the port c to the bottom of the cylinder A, which forces the piston C upward, carrying with it the piston-rod B and the piston F, as well as the frame of sheaves.

The pressure of steam would send the pistons upward with great velocity were it not that the cylinder E is filled with oil or other suitable liquid, so that the upward passage of the 55 pistons is regulated by the capacity of the upward port, a, to discharge the liquid through the passage I into the bottom of the cylinder E, and its capacity may be still further reduced by the proper turning of the plug-valves 60 J, and when the valve K is closed, cutting off entirely the passage of the liquid from one end of the cylinder to the other, immediately the travel of the piston is checked. The piston K should be so arranged as to be operated 65 by the elevator-rope, so that the person in charge of the elevator by the use of this rope inclosing such valve may have perfect control of the elevator. The descent of the piston is governed in the same way, the valve in the 70 steam-chest being reversed to allow the steam in the cylinder A to exhaust itself through the port d. So far as described, the device is designed to be used with steam at high pressure. If it is desired to use low pressure, then 75 the exhaust-steam from the cylinder A through the port d is let into the annular condensing-chamber R, where it is condensed by a spray of cold water through the nozzles S in the manner well known to all mechanical engineers, or in any other desired way. The water thus condensed passes down the passage or 80 passages T to the well U, whence it is drawn by every upward stroke of the piston B by means of the continuation V thereof, which 85 passes through suitable stuffing-boxes, W, in the bottom of the steam-cylinder, and is provided with a piston of the ordinary type used in lift-pumps, which latter works in a barrel, X', connected with the well U, from which the 90 water is discharged through the outlet Y at each upward stroke of the piston B.

A series of sheaves, P, over which another or differential series (not shown) of elevating-cable passes, arranged in a well-known manner, enable me to build an elevator wherein the length of the stroke of the piston C may be multiplied at will, so that a short stroke—say, for instance, of three feet—may be indefinitely multiplied, such multiplication being 100 determined by the number of sheaves employed to obtain the desired lift of the elevator-plat-

form, and by the use of the means for regulating the speed and controlling the position of the platform all danger arising from the direct use of the steam is avoided.

5. What I claim as my invention is—

1. The herein-described combined hoisting device and governor, consisting of the cylinders A E in axial line, the former having openings at one end, and the latter provided with 10 the passage-way I, communicating with both ends of the cylinder, the plug-valves J, located near the end of such passage, and the sliding valve K, intermediately located between the plug-valves, rod B, passing through both cylinders and carrying the pistons C F, respectively working in the cylinders A E, frame O, secured to the upper end of the rod B, and carrying a system of pulleys, P, for the pur-

pose described, the parts being combined, arranged, and operating substantially as and for 20 the purposes specified.

2. The combination of the cylinders A and E, constructed substantially as described, each cylinder having a piston secured to a common piston-rod, B, the upper cylinder being also 25 provided with the communicating-pipe I and its valves, as described, with the condensing-chamber R, well U, and a pump connected therewith and actuated by the movement of the piston-rod B, substantially as and for 30 the purposes set forth.

DAVID KENNEDY.
